WIRE TWISTING MACHINE

John J. Klapper, New Canaan, and Claude C. Smith, Jr., Stratford, Conn., assignors to General Electric Company, a corporation of New York

Filed Jan. 15, 1957, Ser. No. 634,268

3 Claims. (Cl. 57—34)

The present invention relates to a machine for twisting fine wire and particularly to a twisting machine of reduced size having wire pay-offs and take-ups which exert very little tension on the wire.

The twisting techniques used on fine wire of No. 19 AWG and smaller are extremely critical to avoid damaging the wire. Such fine wire usually has a thin wall of insulation of between 10 and 15 mils which cannot withstand abrasion or scuffing without causing deleterious effects on its electrical properties. Also, this fine wire cannot withstand large tensions without experiencing a decrease in its cross-sectional area (necking down) and possibly the breakage of the wire.

Present-day twisting machines use payoff spools or reels which permit unequal wire pay-off resulting in different lengths of singles in the twinned or tripled conductor. This oftentimes results in the rejection of such wire for use in finished cable. In order to twist long lengths of wire, large capacity reels are used which necessarily increase the physical size of the machine. As a consequence, this large size means a bulky, rugged construction which by its very nature cannot delicately handle fine wire. Also, the size and inertia of the twisting machine parts limits the maximum speed of the machine and, hence, its output. In all the present-day machines the wire either has a long path or an intricate path over small sheaves which imparts unnecessary punishment to both the insulation and the copper conductor.

In recent years, work has been conducted on packaging wire in barrels rather than winding it on reels. One advantage of this is that the barrels are usually of heavy duty cardboard construction which results in a light-weight container as compared with a heavy wooden or steel reel. The wire is merely laid in the barrel in a loose pack so that it is an easy matter to place the wire in the barrel and to remove it without exerting much tension on the wire.

Accordingly, the principal object of this invention is to provide a wire twisting machine which is capable of whirling the twisted wire directly into a spinning barrel take-up mechanism.

A further object of this invention is to provide a wire twisting machine with a tensionless wire pay-off and a barrel take-up mechanism to reduce to a minimum the tension which is applied to the wire.

A further object of this invention is to provide a wire twisting machine of small lightweight symmetrical construction which will first twist the wire and then whirl the twisted wire in a revolving helix of more than one turn that is made to revolve at nearly the same speed as the twisting head, so that the twisting motion of the wires at the head will be converted into linear motion before the wire settles in the barrel to provide a level fill from bottom to top.

A further object of this invention is to provide a universal wire twisting machine which is capable of twisting many different combinations of wires, rather than

2

having individual machines for each combination as is the present practice in this industry.

Our invention comprises three main components, namely, a tensionless pay-off which may either be a loose coil of wire, a stationary barrel or a revolving barrel. A stationary barrel will impart some backtwist to the finished twisted conductor. In cases where this backtwist is objectionable, a revolving barrel can be used. The second, and most important, component is the twisting head which revolves at a high speed about a vertical axis and has means for gripping the wires and pulling them through the head as they are being twisted. The pitch of the twisted wire is a function of the amount of travel of the wire through the head for each revolution of the head. 15 This mechanism may either be a pair of endless, caterpillar drive belts in operative engagement which pull the wire therebetween, or two pairs of driven capstans. The capstans would be especially useful for bare copper wire when it is desirable to bunch the copper conductors together. The third and last important component of this invention is a spinning barrel take-up with a central core where the barrel turns at a speed slightly more or less than the linear wire output of the twisting head which, of course, is a function of the speed of the twisting head, so 20 that the twisted wire will level fill the barrel from bottom to top as if the twisted wire were being folded therein rather than dropped directly down into the barrel.

Our invention will be better understood from the following description taken in connection with the accompanying drawings and its scope will be pointed out in the appended claims.

Figure 1 shows a perspective elevational view of two fine wires being drawn down through the twisting head and from there being whirled into the spinning barrel take-up having a central core.

Figure 2 is an isometric view of the details of the twisting head showing a pair of endless belts being driven against each other to pull the two wires downward through the head while at the same time imparting a twist to the wires as the head revolves.

Figure 3 is a plan view of an apertured plate which is assembled over the twisting head and includes a series of protected openings through which the fine wire is drawn from the wire payoff means downward into the twisting head.

Referring in detail to the drawing, and in particular to Figure 1, there is shown a box-like framework 10 of our wire twisting machine having a twisting head 11 near the top and a spinning barrel take-up assembly 12 directly beneath the twisting head. The framework 10 is constructed of a series of angle irons welded together in an open box-like form with a top plate 13, an intermediate shelf 14 on which the twisting head 11 is seated, and a lower shelf 15 supporting a turntable 16 which carries the take-up barrel 12. The lower shelf 15 is raised from the bottom of the framework 10, to allow room for the belt drive mechanism 17 which underlies the turntable 16 and drives the barrel 12 in unison with the twisting head 11.

A pair of stanchions 18 are fixed to the top plate 13 at equal distances from a central opening 19 in the plate. Wires 21 extend through this opening 19 before they enter the twisting head 11. Each stanchion 18 supports a horizontal roller 20 over which the wires 21 move as they are pulled from the wire payoff mechanism (not shown). An apertured plate 22 is supported by the stanchions above the top plate 13 of the machine, and centered over the hole 19 for guiding the wires 21 as they leave the rollers 20 until they extend through the hole 19. This plate 22, as best shown in Figure 3, is of circular configuration with a plurality of small openings 23 arranged in a circular fashion near the edge of the

plate. Each opening 23 has a nylon bushing 24 which reduces the abrasion of the wires 21 as they are being pulled through the opening. Three rods 25 support the plate 22 from the top plate 13 as well as support an intermediate plate 26 having a large size die 27 at its center for gathering the wires together. The twist is actually put into the wires at this die 27, as the twisting head 11 works below the die to grip the wires and twist them together.

An electric motor 30 is mounted toward the back of the framework 10 and combined with a suitable speed reducing variable drive mechanism 31 and 32 so that the relative speeds of the twisting head 11 and the turntable 16 may be altered at will. Although we have illustrated our invention as using a belt drive, it will be understood by those skilled in this art that a chain or gear drive might be preferable under certain conditions where accuracy and precision are prerequisites.

Attention is now directed to Figure 2 of the drawing showing the isometric view of the twisting head 11. The twisting head is supported in the framework 10 by an upper and a lower thrust bearing (not shown) for free rotation about a vertical axis. First, there is a base plate 35 having a central opening 36 through which the wire moves. Over this opening, a pair of wide endless belt drives 37 are vertically arranged in close driving engagement with each other. Each belt runs on a pair of double flanged rollers, the lower one 38 being an idler while the upper one 39 is the driven roller. Both the upper and lower rollers 38 and 39 of each pair are supported from the same vertical support member 40. These supports 40 terminate in a horizontal upper plate 41. A pulley 42 lies flatwise on the plate 41 and is fixed thereto. A V-belt 43 extends around the pulley 42 and is driven by the variable drive mechanism 31 of Figure 1. Thus, as the belt 43 drives V-pulley 42, the twisting head 11 will likewise rotate, carrying the endless belt drive assemblies 37 with it.

The driven roller 39 of the belt drive is controlled by a planetary gear arrangement 44 at the top of the head. Two planet gears 45 meshing with a sun gear 50 are supported above the top face of the pulley 42 and are each free to rotate on a vertical axis. Each gear 45 has a vertical shaft 46 which extends through the pulley 42 and upper plate 41 and has at its lower end a beveled gear 47. This gear meshes with a similar bevel gear 48 that is fixed to the horizontal supporting shaft 49 of the driven roller 39. Thus, as the sun gear 50 is independently driven, the planet gears 45 rotate imparting a drive through bevel gears 47 and 48 to turn the roller 39 that carries the endless belts 37. The sun gear 50 is freely mounted on a hollow shaft 51 that serves as the vertical bearing for the upper portion of the head 11. This gear 50 is fixed to the underside of the loose pulley 52 which is driven by the V-belt 53 from the drive mechanism 31. Accordingly, by varying the speed of rotation of the pulley 52 with respect to the pulley 42, it is possible to obtain a variation in the speed of rotation of the endless belts 37. It is this difference in the relative speeds of the two pulleys 42 and 52 which causes the sun gear 50 to turn with respect to the planet gears 45.

The pitch of the twisted wire is measured along the wire as a distance between one point on the wire and the corresponding point of the next turn of the same wire. This is a function of the speed of rotation of the twisting head and the distance the wire is pulled by the endless belts 37 for each revolution of the head.

Looking at the bottom of Figure 2, it will be understood that the twisted wire 56 is spinning at several hundred revolutions per minute as it is discharged from the twisting head 11 and downward toward the barrel takeup assembly 12. As shown in Figure 1, the barrel 12 has a hollow inner core 57 so that the twisted wire will be packed between the inner side of the barrel and the outer

surface of the core to form a vertical tube of wire. The barrel 12 is suitably fastened at its bottom to the turntable 16 to be driven by the belt drive 17. It must be understood that the rapidly moving twisted wire 56 must be free of all obstructions since it will tend to unwind if it were suddenly grasped by the hand. The solution is to have the barrel 12 spin at a speed that is slightly more or less than the speed of the twisting head 11 so the barrel will either lead or lag behind the output of the head by an amount equal to the pitch of the wire. The speed of the barrel would be measured at a point on the mean circumference of the wire space in the barrel 12 formed by the core 57 and the inner side of the barrel. This may be expressed mathematically as follows:

15 $P = \text{pitch of wire} = \text{one complete helical twist of two or more wires in inches}$

$R.p.m.t = \text{revolutions per minute of twisting head}$

20 $W.O = \text{linear wire output in feet} = \frac{r.p.m.t \times P}{12}$

$MC = \text{mean circumference of wire space where}$

$D_1 = \text{outer diameter of central core in inches}$
 $D_2 = \text{inner diameter of barrel in inches}$

25 $= \pi \sqrt{\frac{D_1^2 + D_2^2}{2}} \times \frac{1}{12}$

$R.p.m.b = \text{revolutions per minute of barrel measured at a point on the mean circumference of the wire space}$

30 $= W.O \times \frac{1}{MC + \frac{P}{12}}$

35 $= \frac{R.p.m.t \times P}{12} \times \left[\frac{1}{\left(\pi \sqrt{D_1^2 + D_2^2} \times \frac{1}{12} \right) \pm \frac{P}{12}} \right]$

The action of the twisted wire as it descends into the barrel 12 may be likened to a cowboy spinning a rope with his hand holding the rope waist high on a vertical axis. The end of the rope extends from his hand and is formed into a helix that terminates in several turns of the rope. As the barrel is near filled, the rotating helix would be shortened into slightly more than one turn as the vertical distance between the head and the level of the wire in the barrel decreases. Thus, as the cowboy moves his hand to spin the rope, a twisting action of the rope at his hand will diminish gradually as it moves toward the free end of the rope in a revolving helix of one or more turns so that there is no twisting or spinning of the free end, but merely linear traveling of the free end about a circular path. If the twisted wire 56 were merely fed into a stationary barrel, the wire would strike the bottom of the barrel and immediately tend to unwind, which of course would be disastrous. For each turn of the twisting head 11 the barrel either leads or lags the head by an amount equal to the pitch of the wire; for instance for a one inch pitch, one inch measured along the mean circumference of the wire space in the barrel. Hence, the wire approaches the barrel almost "dead" so that it settles 60 itself in the barrel in a most surprising manner.

When this invention was first conceived and explained to others working in this art, it was very difficult for them to understand. To our knowledge, we are the first to conceive a wire twisting machine that converts the axial rotation of the wire as it emerges from the twisting head into linear motion by means of a revolving helix of twisted wire of one or more turns as it is delivered into the rotating barrel take-up mechanism. The twisting head turns at a constant speed. When a loop or turn of the helix of twisted wire exceeds the mean circumference of the wire space, the loop will continue to increase in size until it strikes the inner sides of the barrel. For a loop of this size, the head under-delivers and the loop begins to decrease in size until it passes through the mean circumference at which point the head begins to

over-deliver. The loop of wire strikes the inner core first and then begins to grow in size ad infinitum back and forth. Actually, under normal operating conditions the wire will strike the inner surface of the barrel and then will be drawn over to the outer surface of the core and then back again to the inner surface of the barrel until a flower petal pattern is formed in the barrel and builds up successive full layers until the wire space of the barrel is full.

Having described above our novel machine and method for twisting fine wire and packing the twisted wire in a barrel, it should be well understood by those skilled in this art that we have simplified the construction of wire twisting machines and have provided a wire handling method that will carefully treat the wire and tend to eliminate faults in the wires which were produced by the former methods of rough handling the wire. One of our most important contributions is the use of a wire twisting machine that operates about a vertical axis and packs the wire so that the wire does not become untwisted and, hence, unusable.

Modifications of this invention will occur to those skilled in this art, and it is to be understood, therefore, that this invention is not limited to the particular embodiments disclosed but that it is intended to cover all modifications which are within the true spirit and scope of this invention.

What we claim as new and desire to secure by Letters Patent of the United States is:

1. A wire twisting machine comprising guide means for supporting a plurality of wires which are being drawn into the machine, a twisting head rotating about a vertical axis and gripping the wires to pull them over the said guides while putting a continuous twist in the wires, a rotating barrel wire take-up means positioned under the said rotating head to receive the twisted wire as it is delivered from the head, the barrel having a central core so that the wire will fill up the barrel in the wire space around the core, the speed of rotation of the barrel measured as the speed of a point on the mean circumference of the wire space of the barrel, this barrel speed differing from the linear speed of wire output of the twisting head by an amount equal to the pitch of the twisted wire, thereby converting axial rotation of the wire, as it emerges from the twisting head to linear motion by means of more than one complete turn of a revolving helix of twisted wire that is whirled into the barrel take-up means to provide a level fill from bottom to top of the barrel.

2. A wire twisting machine comprising guide means for supporting a plurality of wires being drawn into the machine, a twisting head rotating about a vertical axis and having means for gripping the wires and pulling them over the said guide means, while at the same time putting a continuous twist in the wires having a pitch that is determined as the function of the speed of rotation of the head and the speed at which the wire is pulled by the head, a rotating barrel take-up means positioned under the rotating head to receive the twisted wire as it is delivered from the head, the barrel having a central core so that the wire will fill up the barrel in the wire space around the core, the relation of the speed of delivery of wire from the head with respect to the speed of a point on the mean circumference of the wire space of the barrel take-up means differing only as the function of the pitch of the twisted wire so that the wire will settle into the barrel at a slight acute angle to the bottom of the barrel and will lie neatly in multiple layers, the axial rotation of the wire as it emerges from the twisting head being converted into linear motion by means of more than one complete turn of a revolving helix as the twisted wire is whirled into the barrel.

3. A wire twisting machine comprising guide means for supporting the wires as they travel toward each other for a subsequent twisting operation, the wires being acted upon by a vertically rotating head which pulls the wires over the said guide means while at the same time twisting them continuously around each other, the pitch of the twisted wires being a function of the speed of rotation of the head and the amount the wires are pulled through the head for each revolution of the head, a rotating barrel take-up means located directly under the rotating head so that the twisted wire will drop into the barrel, the speed of rotation of the barrel measured as the speed of a point on the mean circumference of the wire space of the barrel, this barrel speed differing from the linear speed of wire output of the twisting head by an amount equal to the pitch of the twisted wire, the axial rotation of the wire as it emerges from the twisting head being converted into linear motion by more than one complete turn of a revolving helix of wire that is being whirled into the barrel.
